UNITED STATES PATENT OFFICE

ALFRED HOPKINSON, OF HYDE, ENGLAND

BRAIDING MACHINE

Application filed March 16, 1927, Serial No. 175,884, and in Great Britain April 20, 1926.

This invention relates to braiding machines in which two rows or tiers of bobbins are mounted on rotary carriers or races revolving in opposite directions, the threads of the outer set of bobbins being guided under and over the inner set of bobbins by suitable guides and being braided together at a common central point or eye, the bobbin carriers of the inner set sliding or travelling around a circular track and fitted with thread switching plates at the outer ends and the inner bobbin carriers being propelled round the circular track by a series of reciprocating fingers engaging the bobbin carriers or by a system of rollers engaging rollers upon the bobbin carriers.

In this type of machine the bobbin carriers of the inner set are supported either at their outer ends or sometimes at their inner ends and the present invention may be applied to both types of machine.

According to this invention a series of rotary guide discs rotary about their axes loose on fixed or non-rotary pivots and actuated by contact of the threads are mounted upon brackets affixed to a stationary or non-revolving part of the machine to engage or contact in succession with the threads as they are unwound from the outer set of bobbins to direct them over or under the thread switching plate of the bobbin carriers of the inner set of bobbins as required by the pattern, the rotary motion of the discs eliminates friction in lifting the threads and so avoids any pull-back of the threads the discs being kept constantly in motion by the successive contacting of the threads with them. The brackets carrying the rotary guide discs, may be made to swivel or slide into and out of the path of the threads to vary the pattern while the machine is running.

The invention will be fully described with reference to the accompanying drawings.

Fig. 1 is a front elevation of part of braiding machine showing the rotary guide discs F affixed thereto.

Fig. 2 is a sectional elevation of same.

Fig. 3 is a part plan partly in section.

Fig. 4 is a sectional elevation showing a

modified construction with guide disc F above the thread.

Fig. 5 is a front elevation showing modification.

Fig. 5^a is a detail section through the cam plates g, g'.

Figs. 6 and 7 are details of Fig. 5.

Fig. 8 is a part plan showing the invention applied where the inner bobbins are propelled by rollers.

Figs. 9, 10, 11 and 12 are diagrammatic views indicating the path of the thread b.

In the form of the invention shown in Figs. 1 to 3, the machine is constructed in known form with an annular rotating bobbin carrier A for the outer set of bobbins B which also forms a race a for the inner set of bobbin carriers D fitted with switch plates d revolving in the opposite direction, the inner bobbin carriers D being propelled by reciprocating fingers C.

Upon the non-rotary or fixed base E of the machine a number of rotary guide discs F are fitted each projecting into the path of the thread b from the outer bobbins B to guide or direct the threads b over or under the switch plates d of the inner bobbin carriers D. The guide discs F are mounted on fixed pins on brackets f and are adapted to rotate about their own axis to offer little or no friction or resistance to the threads b as they come into contact with them being driven from the rotary shaft E².

The rotary guide discs F may be mounted on ball bearings and are carried on brackets F affixed directly to the base E by screws or otherwise. Or the brackets f' may be affixed to a sliding ring or rings e (Fig. 1) to render the discs adjustable relatively to one another.

The brackets of the rotary guide discs F may be permanently fixed to the base E to give one standard pattern such as one thread over and under the inner bobbin alternately or they may be rendered adjustable relatively to one another to alter or vary the pattern as required. For instance the brackets may be carried by a ring e adapted to be moved round the base E. In the construction shown in Fig. 1 one movable ring e is employed which can be moved to bring the guide discs F together.

in pairs to throw two threads b over and then two threads b under the inner bobbins and set in that position.

In the construction shown in Figs. 5 to 7 5 two movable rings G G' are employed discs F' F^2 and brackets f^2 f^3 being movably mounted upon a base E . The ring G is fitted with cam plates g and the ring G' with cam plates g' and the rings are moved to and 10 fro by a cam or cams H H^3 and as the cam plates g g' come beneath the brackets f^2 f^3 the guide discs F' , F^2 are alternately raised and lowered to bring them into the path of the thread, the cams H , H^3 are mounted on a 15 shaft H^4 and are operated through a train of gearing 4, 5, 6, 7, 8, 9, 10 from the rotary shaft E^3 of the machine.

The pattern can thus be varied during the running of the machine to produce a fancy 20 pattern.

In both arrangements the thread b from each outer bobbin B is carried to a guide eye H' rotating with the bobbin carrier placed at a position below the centre of the switch 25 plate d so that normally the thread will pass under it while the rotary guide discs or plate F will raise it to pass over the switch plate.

While it is preferred to fix the guide eye at a position below the centre of the switch 30 plate a guide eye H^2 may be fixed above the center and a rotary guide disc or plate F^3 in position to depress the thread b' under the switch plate d' , as shown in Figs. 4 and 12.

In the arrangement shown in Fig. 8, the 35 inner bobbin carriers D^2 are propelled by a system of rollers c engaging a roller or rollers C' upon the bobbin carriers D^2 .

In operation as the outer bobbins B revolve the thread b therefrom (see diagrams 9, 10 40 and 11) is raised by each of the rotary guide discs above the nose of each switch plate in succession and passes over the inner bobbin carrier D (Fig. 9) as however the inner bobbins and switch plates are revolving in the 45 opposite direction they alternately assume the position shown in Fig. 10 and the thread b being below the nose of the switch plate 2 passes under it and underneath the inner bobbin. As the next switch plate 3 Fig. 11 50 approaches the thread b it is again raised and passes over the switch plate and so on passing over and under the switch plates in 55 succession as they revolve. A similar action takes place in connection with the construction of Figs 4 and 12, the thread b' being depressed by the rotary guide disc F^3 instead of being elevated by it. The contact of the thread with the rotary discs keep them continually rotating about their axes 60 and so avoids any friction or pull back upon the threads.

What I claim as my invention and desire to protect by Letters Patent is:—

1. A braiding machine of the type described constructed with a series of discs ro-

tary about their axes, fixed nonrotary pins upon which the discs are loosely mounted, brackets by which the pins are carried affixed to the nonrevolving base of the machine the peripheries of the discs contacting with and directing the threads from the outer bobbins over and under the thread switching plates of the inner set of bobbins without friction or pull back upon the threads.

2. A braiding machine comprising in its 75 construction outer and inner sets of bobbins revolving in opposite directions, a series of discs rotary about their axes, fixed nonrotary pins upon which the discs are loosely mounted, brackets by which the pins are 80 carried affixed to a nonrevolving part of the machine, the peripheries of the discs contacting with and directing the threads from the outer bobbins over and under the other set of bobbins without friction or pull back upon 85 the threads and means to move the rotary guide discs relatively to one another to vary and alter the pattern of braid.

3. A braiding machine comprising in its construction outer and inner sets of bobbins 90 revolving in opposite directions, a series of discs rotary about their axes, fixed nonrotary pins upon which the discs are loosely mounted, brackets by which the pins are carried affixed to a nonrevolving part of the 95 machine, the peripheries of the discs contacting with and directing the threads from the outer bobbins over and under the other set of bobbins without friction or pull back upon the threads and a movable adjustable 100 ring upon which some of the rotary guide discs are carried to permit of their relative adjustment to vary or alter the pattern of braid.

4. A braiding machine having rotary 105 guide discs relatively adjustable as in claim 3 and means to give a rotary movement to the ring upon which the discs are carried.

In testimony whereof I have hereunto set my hand.
